EVAPORATOR

Filed May 5, 1927

UNITED STATES PATENT OFFICE.

SALLIE ROSENTHAL, OF HAMBURG, GERMANY.

EVAPORATOR.

Application filed May 5, 1927. Serial No. 189,051.

This invention relates to an evaporator designed particularly for the use of perfume and also utilizable in a more or less degree as a lamp or source of illumination, where-
5 by the article may become highly desirable for use on a dressing table or the like.

The principal object of the invention is the provision of a transparent container adapted to house an interior source of il-
10 lumination, with an interior receptacle de-
signed to contain perfume or the like which, under evaporation incident to the heat from the source of illumination, discharges such volatile product into the immediately sur-
15 rounding air.

The invention is illustrated in the accom-
panying drawings in which:

Figure 1 is a view in elevation, partly in section, showing the improved evaporator.
20 Figure 2 is a similar view showing a slightly modified form.

Figure 3 is an elevation of the evaporator in a further modified form.
The improved evaporator comprises, in
25 the preferred form, a substantially oval cas-
ing 1 having a somewhat flaring lower skirt
portion 2, with the lower edge of the latter
undulating to provide openings 3 between
the lower edge of the skirt and the surface
30 on which the evaporator is resting. The upper
edge of the casing is reduced in the form
of an annular band 4 formed with perfora-
tions 5 and above the band is secured an
ornamental top or cap 6.

Within the main length of the casing 1 there is arranged a receptacle 7 preferably
35 through an annular wall 8 concentric or
substantially concentric with the wall of the
casing, which wall at its upper and lower
ends, as at 9 and 10, is extended laterally to
40 form the receptacle 7 wholly independent
of and closed against the interior of the cas-
ing. The lower portion of the receptacle 7
may, if desired, be provided with absorbent
45 material 11 and the wall of the casing which
forms the outer wall of the receptacle 7 is
formed with an annular series of perfora-
tions 12, one of which, as 13, may be en-
larged to form a filling opening.

An ordinary incandescent light socket 14
50 is supported in the center of the casing prop-
er, preferably at the juncture of the casing
and skirt, this socket being supported on a
hollow rod 15 mounted in one wall of the
55 skirt and through which extends a member
operated by a wing nut 16 for controlling

the usual switch in the socket. The detail of the switch control is not important and is not illustrated, it being understood that the function of the wing nut 16 is merely to 60 close and open the usual socket switch. The circuiting wires 17 extend through an opening in the skirt and are connected to the socket in the usual manner, and an incan-
descent lamp 18 of appropriate size is placed 65 in the socket in the usual manner.

Perfume is placed in the receptacle 7 to
the desired extent, and as the walls of the
receptacle and of the casing are transparent
or translucent, that is constructed of glass,
70 porcelain or other similar material, it is
apparent that the light will be transmitted
through the walls to an appreciable extent,
permitting the evaporator to serve to some
75 extent as a lamp. The heat from the incan-
descent lamp will tend to some slight evapo-
ration of the perfume in the receptacle 7 and
the volatile product will escape through the
openings 12 into the surrounding atmos-
phere. The structure is maintained at an 80
appropriate degree of heat through the out-
let afforded the heated air through the open-
ings 5, the openings 3 at the bottom of the
skirt permitting an inflow of cool air to pre-
vent overheating the structure. 85

It is obvious that the casing 1 may be con-
structed in various forms, as for example in
Figure 2, the casing here indicated at 19 is
shaped to more or less simulate the body of
an animal, the upper portion, indicated at
90 20, simulating the head of the animal. The
openings for the escape of heated air at 21
are formed in the head and the bottom por-
tion of the casing has the usual air inlets
22. In this form, the perfume receptacle,
95 similar to the receptacle 7 in the preferred
form, is indicated at 23 and is formed by a
single wall 24 connected at its upper and
lower ends to a portion of the casing wall
and spaced therefrom to provide the recep-
tacle. The vapor outlets 25 are formed in
100 the wall of the casing at the top of the re-
ceptacle.

Figure 3 shows a slightly different form
in which the casing, here shown at 26, is
105 substantially similar to that shown in Fig-
ure 1, having the skirt 27, air inlets 28, cap
29 and heated air outlets 30. In this form,
the perfume receptacle, indicated at 31, is
exactly similar to the perfume receptacle of
Figure 2, having the vapor outlets 32 and
110 filling opening 33.

Of course, the forms shown in Figures 2 and 3 are constructed to receive an incandescent lamp and made up of transparent or translucent material.

5 What I claim to be new is:

A perfume evaporator, comprising a transparent casing formed with air inlets at the bottom, a cap at the upper end of the casing formed with air outlets, a transparent 10 wall arranged inwardly of and extending entirely around the casing between the inlet and outlet openings to form a receptacle, the upper portion of the wall being flared out-

wardly toward the casing, the inwardly extending wall forming a central passage, the 15 casing having a series of openings formed adjacent the flared upper portion of the wall, the latter deflecting the fumes from the receptacle to the openings, a support within the casing below the inner wall, and a lamp 20 located in and wholly free of contact with the wall of the central passage and mounted on the support.

In testimony whereof I affix my signature.

SALLIE ROSENTHAL.
